UNITED STATES PATENT OFFICE.

FRANK B. HOWELL, OF BUFFALO, NEW YORK, ASSIGNOR TO AMERICAN RADIATOR COMPANY, OF CHICAGO, ILLINOIS, A CORPORATION OF NEW JERSEY.

BOILER.

Application filed December 23, 1920. Serial No. 432,689.

My invention relates to improvements in heating apparatus, and the same has for its object more particularly to provide a boiler for heating purposes capable of insuring the highest efficiency for the fuel consumed.

Further, said invention has for its object to provide a boiler having a combustion chamber interposed between the fuel receptacle and the flues, in which the products of combustion are caused to strike or impinge against a wall of heated refractory material, in order to effect the complete and economical combustion of the gases entering said combustion chamber.

Further, said invention has for its object to provide a boiler having a vertical fuel receptacle, and a vertical combustion chamber arranged to the rear thereof and communicating therewith whereby the products of combustion, as they pass from the fuel receptacle in said combustion chamber, will be retarded or delayed in order to effect the due consumption of any combustible gases which may be liberated in the fuel receptacle and pass unconsumed therefrom.

Further, said invention has for its object to provide a sectional boiler having a vertical fuel receptacle therein, and a relatively narrow vertical combustion chamber arranged to the rear of said fuel receptacle and substantially co-extensive in width and height therewith.

Further, said invention has for its object to provide a boiler in which all the air necessary to support combustion is received in the top of the boiler, above the fuel magazine, and then fed downwardly within the boiler, preheated, and delivered in said condition into the fuel receptacle to the burning fuel therein.

Further, said invention has for its object to provide a boiler formed of a plurality of corresponding sections having registering openings therein forming a combustion chamber and having one of its walls provided with a facing of refractory material.

Other objects will in part be obvious, and in part be pointed out hereinafter.

To the attainment of the aforesaid objects and ends, my invention consists in the novel details of construction, and in the combina-

tion, connection and arrangements of parts hereinafter more fully described, and then pointed out in the claims.

In the accompanying drawings—

Figure 1 is a front elevation illustrating one form of boiler constructed according to, and embodying my invention;

Figure 2 is a vertical section taken on the line 2—2 of Figure 1; and

Figure 3 is a horizontal section taken on the line 3—3 of Figure 2.

In said drawings 10 designates a sectional boiler of the cross-draft type comprising hollow end sections 11, and a series of intermediate sections 12, each comprising a front member 12^a, and a back member 12^b. The front members 12^a, and the back members 12^b are connected together at their upper and lower ends in two transverse series by nipples 12^c.

The two transverse series of connected members are arranged in spaced relation to each other to form therebetween a vertical fuel receptacle 13, and at their opposite ends, adjacent to the tops and bottoms thereof, said transverse series are connected by nipples to the end sections 11.

Each front member 12^a is provided at its lower end with an inwardly and downwardly inclined toe 14, and above said toe with a relatively narrow portion 15 provided upon its opposite sides with laterally-extending downwardly and inwardly inclined fins 16 whose outer edges register with the corresponding edges of the fins on the adjoining sections and form air inlet passages 17 communicating with a vertical air duct 18 provided in the upper wider portion of the member 12^a, and formed between the members 12^a by the laterally-extending ribs 18^a, 18^b. The upper ends of said air ducts 18 communicate with the upper portion of the fuel magazine.

The front portion of each back member 12^b is provided adjacent to its upper end with oppositely-extending vertical ribs 26^a which extend downwardly towards the base of said back member 12^b, below which each of said members is provided with a relatively narrow portion 20 provided upon the opposite sides with laterally-extending up-

wardly and rearwardly inclined fins 20^a whose edges register with the corresponding fins of the adjoining sections and form passages 21 through which the products of combustion may pass.

Directly to the rear of the laterally-extending ribs 26^a, each member 12^b is provided with oppositely-extending slightly inclined ribs 22 whose lower ends terminate a short distance above the lower edges of said members 12, and form a horizontal, forwardly-extending flange 22^a, and an outlet opening 23 below the same. 22^b denotes similar horizontal forwardly-extending flanges arranged about midway of the height of the rib 22.

The space in the back members 12^b intermediate said ribs 22, and the ribs 26^a and the fins 20^a constitutes a combustion chamber 19 whose several parts communicate with the several flues 24.

In order to cause said combustion chamber to be maintained at a higher temperature than otherwise would be possible, the portion of its rear wall between the horizontal flanges 22^a, 22^b is provided with a lining 19^a formed of fire brick or other suitable refractory material. The combustion chamber 19 is substantially coextensive in height with the fuel receptacle and flues, and also substantially coextensive in width therewith, the width of said combustion chamber equaling the distance between the end sections 11.

The top, back and lower edges of the intermediate back members 12^b, as well as the peripheral edges of the end sections 11, are provided with laterally-extending, registering ribs 26 which are interrupted or broken away to accommodate certain doors and parts hereinafter described.

Each back member 12^b is provided upon its opposite sides adjacent to its center with laterally-extending horizontal ribs 27 which extend inwardly from the rear edge of said member and terminate near the center thereof, and below said ribs 27 with similar ribs 27^a which extend from the inclined rib 22 inwardly and terminate near the center of said member 12^b, and serve as baffles to form an S-shaped passage or flue extending from the outlet opening 23 to the collecting flue 25 formed at the upper rear corners of said back members 12^b by cutting a quadrant-shaped portion from each of said members. 31 denotes a flanged collar secured to the back of the rear members 12^b to receive a pipe by means of which the boiler may be connected to a chimney or stack.

It will, of course, be understood that the end sections 11 are each provided with rib parts 18^c, 18^d, 22^a, 26^b, 26^c, which register with the corresponding parts 18^a, 18^b, 22^c, 26^d, etc. of the adjacent faces of the intermediate section members 12, 12^b.

The assembled boiler sections 11, 12 and 15 the contained parts are enclosed by a metallic

jacket 32 having a heat insulating lining, provided upon its inclined front portion with a fuel opening 45^a having a cover 45, and at its lower front portion with an ash pit opening 35 closed by a door 36. Above the ash pit opening is a slicing opening 33 having a door 34.

In the top of the casing is an air inlet opening 37 communicating with the upper portion of the fuel receptacle or magazine 13. The said air inlet opening 37 is controlled by a damper 38 connected to one end of a lever 39 of a thermosensitive, automatic regulator 40. The other end of said lever 39 is pivotally connected to a check damper 41 controlling an air inlet opening 42 provided in the top of the boiler and communicating with the collecting flue 25.

The rear wall of the boiler is provided at about its middle with a flue cleanout opening 43, provided with a door 44.

46 denotes a supplemental air supply tube extending through the upper portion of the combustion chamber 19, and having its ends, which extend through the side members 11, provided with controlling dampers or valves 47.

The operation of the boiler is as follows: Fuel is introduced in the fuel receptacle 13 through the openings 45^a, and then ignited. The air necessary to support combustion is admitted to the upper portion of the fuel receptacle 13 through the opening 37 which is automatically controlled by the damper 38, and then caused to pass downwardly in a plurality of separated streams through the air ducts 18 and thence pass through the openings 17 provided between the inclined fins 16 at the lower end of the front members 12^a. The products of combustion and any unburned gases liberated by the fuel will pass through the outlet passages 21 between the inclined fins 20^a at the lower front ends of the rear members 12^b thence pass into the combustion chamber 19 and first strike or impinge upon or against the wall of refractory material 19^a and impart some of their heat thereto. The arrangement of the fins 21 and the passages 20^a in the back members 12^b is such that the products of combustion and unconsumed gases will initially be directed upwardly and against the wall of refractory material 19^a, and momentarily retarded, whereupon the same finally pass downwardly and through the opening 23 into the flues 24. The hot gases then pass upwardly in an S-shaped course through said flues 24 to and into the collecting flue 25 and thence to the stack.

It is to be noted particularly that as all air supplied to the burning fuel is admitted through the opening 37 in the top of the fuel receptacle 13, and thence caused to pass through the air ducts, it will become pre-heated before it reaches the incandescent fuel

ceptacle, two laterally extending vertical ribs arranged in spaced relation upon the opposite sides of each of said back members and registering with the corresponding ribs of adjacent sections and forming a combustion chamber having passages adjacent to its lower end extending from the fuel receptacle to said combustion chamber, and laterally-extending horizontal ribs arranged in spaced

10 relation upon the opposite sides of said back members between said combustion chamber and the smoke outlet; said ribs extending alternately from the rear edges of said back members and the rear wall of said combustion chamber and having their inner ends terminating about midway between the same, substantially as specified.

15 8. In a boiler, a fuel receptacle, a front wall for said receptacle having openings 20 therein for admitting air thereto, a duct in said front wall communicating with said openings and with the upper portion of said fuel receptacle, and means for admitting air to the upper portion of said fuel receptacle, substantially as specified.

25 9. In a boiler, a fuel receptacle, a front wall for said receptacle having openings

therein adjacent to its lower end for admitting air thereto, a plurality of ducts in said front wall communicating with said openings, and with the upper portion of said receptacle, and means for admitting the air necessary to support combustion to the upper portion of said fuel receptacle, substantially as specified. 30

10. In a boiler, a fuel receptacle, a front wall for said receptacle comprising a series of hollow, water-backed members, fins extending from the opposite sides of said members and forming air passages therebetween, laterally-extending peripheral ribs arranged at the opposite sides of the upper portions of said members along the edges thereof and forming a plurality of separated air ducts 35 communicating at their lower ends with said air passages and at their upper ends with the upper portion of said fuel receptacle for supplying preheated air to said fuel receptacle, substantially as specified. 40

FRANK B. HOWELL

or the combustible gases, and thereby insure the complete combustion of the fuel without unduly lowering the temperature thereof.

Further, it is to be noted that by the provision of the relatively narrow combustion chamber 19 to the rear of the fuel receptacle, and the lining of the rear wall thereof with a suitable refractory material 19^a, the products of combustion are initially delayed therein in their passage to the flues, and caused to impart some of their heat to the walls of said combustion chamber and thereby insure the maintaining of said combustion chamber at extremely high temperature, which results in all gases liberated by the fuel being completely consumed.

Having thus described my said invention what I claim and desire to secure by Letters Patent is:—

20 1. A boiler comprising a fuel receptacle, flues at the rear thereof, spaced vertical walls intermediate said fuel receptacle and said flues forming a relatively narrow combustion chamber disposed vertically between the same, a lining of refractory material upon the lower portion of the rear wall of said combustion chamber, openings in the front wall of said combustion chamber for receiving the products of combustion and directing the same transversely of said chamber against said lining, and means for supplying secondary air to said combustion chamber at the upper end thereof; said combustion chamber communicating with said flues at the lower end thereof, substantially as specified.

25 2. A boiler comprising a fuel receptacle, flues at the rear thereof, a vertical combustion chamber arranged between said fuel receptacle and said flues, and substantially coextensive in height and width therewith; said combustion chamber becoming larger in area as it approaches the top, an outlet to said flues at the lower end of said combustion chamber, and openings in the front wall of said combustion chamber for receiving the products of combustion and directing the same against the rear wall of said combustion chamber; said openings being arranged to direct the products of combustion towards the enlarged end of said combustion chamber opposite said outlet, substantially as specified.

30 3. A boiler comprising a fuel receptacle, flues at the rear thereof, a narrow vertical combustion chamber interposed between said fuel receptacle and said flues and becoming larger in area as it approaches the top, an outlet to said flues at the lower end of said combustion chamber, and a lining of refractory material upon the rear wall of said combustion chamber; the front wall of said combustion chamber having rearwardly and upwardly inclined openings therein for receiving the products of combustion and di-

recting the same upwardly against said lining, substantially as specified.

4. A boiler comprising a fuel receptacle, flues at the rear thereof, a relatively narrow vertical combustion chamber arranged between said fuel receptacle and said flues, an outlet to said flues at one end of said combustion chamber, and means disposed towards the opposite end of said combustion chamber for supplying secondary air thereto; the front wall of said combustion chamber having inclined openings therein for receiving the products of combustion and directing the same towards said secondary air means and against the rear wall of said combustion chamber, substantially as specified.

5. A boiler comprising a vertical fuel receptacle, flues at the rear thereof, a vertical combustion chamber having a relatively narrow base portion increasing in area as it approaches the upper end thereof arranged between said fuel receptacle and said flues; and a lining of refractory material upon the rear wall of said combustion chamber; the front wall of said combustion chamber having rearwardly and upwardly inclined openings therein for receiving the products of combustion and directing the same against the refractory lining upon the rear wall of said combustion chamber, substantially as specified.

6. A boiler comprising end sections, and a plurality of intermediate sections each comprising a front member and a back member arranged in spaced relation thereto and forming a fuel receptacle therebetween, two laterally-extending vertical ribs provided in spaced relation upon the opposite sides of each of said back members and registering with the corresponding ribs of adjacent sections and forming a relatively narrow combustion chamber substantially coextensive in height and width with said fuel receptacle and of increasing area from bottom to top, the outermost of said ribs being correspondingly recessed adjacent to their lower ends to form passages extending from the base of said fuel receptacle to the base of said combustion chamber, and flues formed intermediate said back members extending from said combustion chamber to the smoke outlet of the boiler, substantially as specified.

7. A boiler comprising end sections, and a plurality of intermediate sections each comprising a front member and a back member arranged in spaced relation thereto and forming a fuel receptacle therebetween, a housing enclosing said sections and provided with an air inlet opening communicating with said fuel receptacle; said front member having a plurality of air inlets therein communicating with said fuel receptacle, and a plurality of air ducts connecting said air inlets with the upper portion of said fuel re-
